CONVERTIBLE GAME AND DINING TABLE

Myron Freeman, North Hollywood, Calif., assignor to Sunshine Cover and Tarp, Inc., North Hollywood, Calif.

Filed Nov. 19, 1973, Ser. No. 417,099

Term of patent 14 years

Int. Cl. D21—01

U.S. Cl. D34—3

FIG. 1

FIG. 2

FIG. 3.

FIG. 4.

FIG. 5.

FIG. 1 is a plan perspective view of a convertible game and dining table showing my new design;

FIG. 2 is a side view thereof;

FIG. 3 is a plan view thereof with the top removed;

FIG. 4 is a bottom plan view of the removed top thereof; and

FIG. 5 is a sectional view thereof, taken along line 5-5 of FIG. 2.

The sides, not shown, are similar to the respective sides illustrated.

The characteristic feature of my design resides in the configuration of the table supports.

I claim:

The ornamental design for a convertible game and dining table, as shown and described.
